AUTOMOBILE BUMPER JACK

Mitchell C. Caster, Akron, Ohio

Application March 5, 1953, Serial No. 340,617

3 Claims. (Cl. 254—99)

This invention relates to lifting jacks, and in particular relates to bumper-type lifting jacks for vehicles.

Heretofore, there has been available on the market a bumper-type lifting jack in which one leg of a tripod constitutes a housing for a screw rod which carries a bumper-engaging lifting member adapted to be raised and lowered by turning the screw rod. One difficulty encountered with this type of jack has been that said casing and screw rod usually extend at an angle to the vertical and a load on the lifting member tends to flex or bend the screw rod, thereby causing a binding action between the lifting member and the rod which seriously hampers raising and lowering of the lifting member.

One object of the present invention is to provide a lifting jack of the character described having improved means for preventing a load on the lifting member from flexing or bending the screw rod which carries the same, and thereby obviating binding action between the parts which would otherwise prevent free movement of the lifting member longitudinally of the screw rod.

Another object of the invention is to provide an improved lifting jack of the character described including a screw rod rotatably mounted in an elongated housing or hollow support, and a lifting member carried by the screw rod in threaded connection therewith to be moved longitudinally of the support upon rotation of the screw rod, the improved structure including anti-friction means between the lifting member and said housing whereby a minimum of manual effort is required to rotate the screw rod for moving the lifting member with a load thereon.

Another object of the invention is to provide a lifting jack of the character described in the last paragraph, wherein the lifting member has a freely projecting load-engaging hook portion which is readily removable to make the jack more compact, as for shipping or storage purposes, without disturbing the screw connection between the lifting member and screw rod.

Other objects of the invention will be manifest from the following brief description and the accompanying drawings.

Of the accompanying drawings:

Figure 1 is a perspective view of the lifting jack embodying features of the invention.

Figure 2 is a fragmentary side elevation, partly broken away and in section, of the lifting member portion of the jack shown in Figure 1.

Figure 3 is a horizontal cross-section taken substantially on the line 3—3 of Figure 2.

Figure 4 is a side elevation corresponding to Figure 2, but illustrating parts of the jack in exploded condition.

Figure 5 is a vertical cross-section of a portion of a lifting jack of the type shown in Figures 1 to 4, but illustrating a modified form of lifting member.

Figure 6 is a horizontal cross-section taken substantially on the line 6—6 of Figure 5.

Figure 7 is a view similar to the upper portion of Figure 5, illustrating another modified form of lifting mem-

2

ber for the same general type of lifting jack as described above.

Figure 8 is a horizontal cross-section taken substantially on the line 8—8 of Figure 7.

Referring first to the form of the invention shown in Figures 1 to 5, the numeral 10 designates a lifting jack having a lifting member 11 supported in threaded connection on a screw rod 12, which is manually rotatably mounted to extend longitudinally within an elongated tubular support 13. The jack shown is of the collapsible tripod type, wherein the support 13 constitutes a forward leg thereof, braced or supported at an upward inclination to the horizontal by a pair of rearwardly extending legs 14, 14 pivotally connected to downturned lugs 16, 16 on a head plate 17 welded or otherwise attached to the upper end of support 13. Lengths of chain 18, 18 between adjacent legs 13 and 14, 14 limit outward separation of the legs in the operative condition of the jack, as shown in Figure 1. Feet or base members 19 and 20, 20 are pivoted on the lower ends of the front leg or support 13 and rear legs 14, 14, respectively, to provide requisite solid positioning of the jack on supporting surfaces of various kinds.

For rotatably mounting the screw rod 12 within the tubular leg or support 13 the same may be suitably suspended from a thrust bearing 22 between an enlarged head 23 on the upper end of the rod and the head plate 17, which is apertured to receive the rod. Rod 13 is restrained against wobbling action by the lifting member in a manner which will be apparent later. A suitable handle 24 pivotally attached to the head 23 is manually operable to rotate the screw rod.

As best shown in Figures 2, 3 and 4, the lifting member 11 may be of segmental construction, including a freely projecting bumper-engaging lifting hook part 25, a nut 26, and a retaining plate 27. The nut 26, which has the screw rod 12 threaded therethrough, may be of square horizontal cross-section corresponding to horizontal cross-section of the tubular support 13, and has a reduced forward extension 28 protruding through a longitudinally extending slot 29 in the support defining opposite inturned flanges 30, 30 in the forward wall of the support, said extension 28 providing laterally opposite shoulders 31, 31 on the nut which slidably engage the inner faces of said flanges 30, 30. Extension 28 is of rectangular vertical cross-section to be relatively non-rotatably received through a correspondingly shaped slot 32 in said retaining plate 27, which is slidably retained against the upwardly inclined forward faces of said support flanges 30, 30, across said slot 29. Lifting hook 25 may be formed of sheet metal to provide a narrow upper web portion 33 and laterally spaced downturned sidewalls 34, 34 adapted to have inner end portions thereof embrace the extension 28 protruding through the plate 27 (see Figure 2). For retaining plate 27 against the support flanges in this manner, aligned apertures 35 and 36, 36 are provided in the nut projection 28 and walls 34, 34 of the lifting hook 25 to receive a bolt 37 therethrough, so that straight inner edges 38 of the walls engage flatly against the outer face of plate 27. Thus the three principal elements of the lifting member 25 are assembled as a unit to be in vertically slidably tongue-and-groove relation as to the forward flanges 30, 30 of the support 13, as best illustrated in Figures 2 and 3. The lifting hook 25 may have a rearwardly projecting tang 39 engageable between the top face of nut 28 and the upper end of the slot 32 in plate 27, to make sure that the parts of the lifting member will be held in firmly assembled relation. As best shown in Figure 2, the web portion 33 of lifting hook 25 extends forwardly of the support 13 at an upward inclination from a point of supporting engagement of tang 39 with the top of the nut 28, so

that if the bolt 37 has a loose fit in the aligned apertures 36 of the lifting hook, as shown, a substantial proportion of a load pressure on the lifting hook will be translated into rearward pressure of the inner edges 38 of sidewalls 34 against the retaining plate 27. Thus, the load on the lifting hook 25 is substantially self-operating to maintain a requisite degree of frictional engagement between the retaining plate and support flanges 30, 30 to assure smooth, uniform vertical movement of the lifting member 11.

In operation or use of the lifting jack described above it is positioned in the extended condition shown in Figure 1 to have the lifting hook 25 of lifting member 11 under the bumper of an automotive vehicle, for example. Next, the operator manually turns handle 24 to rotate screw rod 12 in proper direction to urge the lifting member upwardly, first to engage the bumper (not shown) and then to lift the vehicle, in known manner. Because there is a certain degree of flexibility between the lifting hook 25 and nut 26, and the load to a substantial extent being carried by the support 13 through the inclined retaining plate 27, as described, frictional binding action due to the tendency of such load on the hook to apply moments to the nut which would flex or bend the screw rod is reduced to a minimum.

The above described jack has a further advantage of being economical to ship or store, in that the lifting hook 25 is detachable from nut 26 upon removal of the bolt 37, thereby to obviate the projection of said hook from the support 13 which would otherwise occupy a substantial space necessarily extending the full length of the usual shipping container for the jack.

Referring to Figures 5 and 6 there is illustrated a portion of lifting jack 40 which is similar to the jack 10 shown in Figures 1 to 4, except that it has incorporated therein a modified form of lifting member 41. As before a tubular support 42 of square cross-section constitutes an inclined forward leg of a tripod type of jack, as shown in Figure 1, said support having an elongated slot 43 in the forward wall thereof defining oppositely disposed flanges 44, 44.

The lifting member 41 may include a square nut 45 threaded on a screw rod 46, corresponding to screw rod 12, and a lifting hook having an integral bifurcated portion 47 in sliding tongue-and-groove connection with said flanges 44, laterally opposite sidewalls 48, 48 of the bifurcation embracing the nut 45 and being apertured to receive opposite pivot pin extensions 49, 49. In other words, and for purposes to be described, the nut 45 has a requisite degree of pivotal action with respect to the lifting member 41, in the direction of a plane at right angles to a laterally extending axis through the pivot pin extensions 49.

The jack shown in Figures 5 and 6 is operated substantially as before. Upon application of load to lifting hook 42, however, the pivotal connection between the same and nut 45 is self-operating upon application of bending or flexing stresses to the screw rod to prevent binding action tending to retard manual turning of the screw rod.

Referring now to Figures 7 and 8, there is shown another modified form of lifting member 51 for a jack of the type previously described, said lifting member having an enlargement 52 received within a channel-shaped upright support 53 and apertured for somewhat loose sliding reception of a screw rod 54. The enlargement 52 is supported on top of a nut 55 threaded on screw rod 54 and is held in axial alignment with the screw rod by a roller 56 between spaced lugs 57, 57 integral with said enlargement and extending rearwardly at opposite sides of the support, said roller being in rolling engagement with a rear wall 58 of the support at a point substantially above the level of an integral forwardly extending load-engaging hook 59. For preventing rotation of nut 55 with respect to rod 54, the same may be cylindrical with flat opposite ends 60, 60

in sliding engagement with opposite side flanges 61, 61 of support 53.

In operation of the structure described in connection with Figures 7 and 8 the lifting member 51 is carried vertically by the nut 55 upon rotation of screw rod 54, the roller 56 allowing such movement without substantial frictional resistance. Any possible wobbling action of the lifting member 51 under load will not be transmitted to the nut, and hence bending of the screw rod which would cause binding action between the nut and the rod is thereby obviated.

Obviously features of the several forms of invention shown may be interchanged. As an example, the roller type lifting member 51 shown in Figures 7 and 8 may be provided with the pivoted nut construction shown in Figures 5 and 6, or with the separable segmental construction shown in Figures 1 to 4, or with combinations of both of these constructions. Similarly, the lifting member 11 shown in Figures 1 to 4 may have the pivoted nut construction of Figures 5 and 6 or the separable nut construction shown in Figures 7 and 8.

Other modifications of the invention may be resorted to without departing from the spirit thereof or the scope of the appended claims.

What is claimed is:

1. A lifting jack comprising an elongated hollow support having laterally spaced sides and a front wall provided with a longitudinally extending opening in the same, means for supporting said support with said front wall presented at an angle to the horizontal, a threaded post rotatably mounted on said support to extend longitudinally between said sides, a nut threaded on said post, a lifting member having spaced portions within said hollow support non-rotatably embracing laterally opposite sides of said nut and to be non-rotatable with respect thereto in direction about the axis of the post, said member being pivotally connected to said embracing portions to pivot relatively of the same in direction of a plane through said axis of the post and said opening, thereby to obviate binding action between the nut and said post with bending of the post under a load on the member, said member having a work-engaging hook portion extending freely outwardly of said longitudinal opening, said spaced portions of the member having opposite sides thereof longitudinally slidably engageable with said laterally spaced sides of said support to prevent relative rotation of the same and said nut about the axis of the post as the post is rotated, and means for rotating said post about said axis and thereby to move said nut and member in either direction longitudinally of the support, said member having portions bearing downwardly against said front wall of said support to support some of the load on the element.

2. A lifting jack comprising an elongated hollow support having laterally spaced sides and a front wall provided with a longitudinally extending opening in the same, means for supporting said support with said front wall presented at an upward inclination to the horizontal, a threaded post rotatably mounted on said support to extend longitudinally between said sides, a nut threaded on said post, a lifting member having spaced integral portions received within said hollow support and embracing laterally opposite sides of said nut and to be non-rotatable with respect thereto in direction about the axis of the post, said nut being pivotally connected to said embracing portions to pivot relatively of the same in direction of a plane through said axis of the post and said opening, thereby to obviate binding action between the nut and said post with bending of the post under a load on the member, said member having a work-engaging hook portion extending freely outwardly of said longitudinal opening, said spaced portions of the member having opposite sides thereof longitudinally slidably engageable with said laterally spaced sides of said support to prevent relative rotation of the same and said nut

about the axis of the post as the post is rotated, and means for rotating said post about said axis and thereby to move said nut and lifting member in either direction longitudinally of the support, said member having portions bearing downwardly against said inclined front wall of said support to support some of the load on the member and thereby to relieve a corresponding degree of the load on said nut.

3. A lifting jack comprising an elongated hollow support having laterally spaced sides and a front wall provided with a longitudinally extending opening in the same, means for supporting said support with said front wall presented at an angle to the horizontal, a threaded post rotatably mounted on said support to extend longitudinally between said sides, a nut threaded on said post, a lifting member having spaced portions within said hollow support non-rotatably embracing laterally opposite sides of said nut and to be non-rotatable with respect thereto in direction about the axis of the post, said nut being pivotally connected to said embracing portions to pivot relatively of the same in direction of a plane through said axis of the post and said opening, thereby to obviate binding action between the nut and said post with bending of the post under a load on the member, said member having a work-engaging hook portion extending freely outwardly of said longitudinal opening, said spaced portions of the member having opposite

sides thereof longitudinally slidably engageable with said laterally spaced sides of said support to prevent relative rotation of the same and said nut about the axis of the post as the post is rotated, and means for rotating said post about said axis and thereby to move said nut and member in either direction longitudinally of the support, a load on said member thereby through said nut tending to bend said post, said member having portions bearing downwardly against said front wall of said support to support some of the load on the member, said longitudinal opening being defined by opposite inturned flanges on said post, and said member having longitudinally extending grooves slidably receiving said inturned flanges of the lifting element.
